UNITED STATES PATENT OFFICE.

HENRY G. HAROLD, OF BROOKLYN, NEW YORK.

GARMENT HANGER.

Application filed November 21, 1922. Serial No. 602,404.

To all whom it may concern:

Be it known that I, HENRY G. HAROLD, a citizen of the United States, residing at Brooklyn, in the county of Kings and State 5 of New York, have invented certain new and useful Improvements in Garment Hangers, of which the following is a specification.

This invention relates to folding coat hangers and more particularly to a novel 10 and improved hanger which may be collapsed in a comparatively small condition and opened so as to accommodate a garment when ready for use.

The primary object of my invention is the 15 provision of a hanger wherein the arms are pivoted to each other at a point adjacent a supporting hook and in which the arms are provided with pivoted, folding extensions adapted to lie and be concealed within the 20 first mentioned pivoted arms when the coat hanger is collapsed.

Another and equally important object of 25 my invention is the provision of a collapsible hanger wherein the main pivoted arms are provided with extensions that fold within the same somewhat in the nature of the blades of a knife including means for securing a supporting hook which lies substantially flush with the respective arms when 30 the hanger is folded.

I accomplish the above objects and others 35 which will become more apparent as the description proceeds and when taken in connection with the accompanying drawings, showing a preferred embodiment of my invention and wherein;

Figure 1 is a view showing the hanger extended and the manner of folding the extensions.

Figure 2 is a plan view.

Figure 3 is a view partly in section showing the means for pivoting the arms and securing the supporting hook.

Figure 4 is a plan of the hanger when 45 folded and in collapsed position, and

Figure 5 is a top view of the hanger as shown in Figure 4.

Referring now to the drawings wherein 50 like reference characters designate corresponding parts throughout the several views, 5, 6, designate a pair of main supporting arms which are substantially U-shaped in cross section, which may be constructed of metal, wood, fibre or any other material as manufacturing and cost necessities may require. The inner ends of the arms 5 and 6

are each pivotally connected as at 7, 8, by rivets or any other suitable means to a central block 9, the latter being adapted to receive the threaded end 10 of a supporting hook 11 which hook is curved as indicated at 12 so that when the hanger is folded, the hook will lie substantially flush with the respective arms 5, 6, as clearly indicated by Figures 4 and 5 of the drawings. Pivotally 60 secured to the outer ends of the arms 5 and 6, I have provided a pair of extensions 13, 14, having enlargements 15 on the extreme outer ends thereof to more properly engage a garment and the shoulder portion and adjacent the sleeves so that the same will lie properly on the hanger. It will be observed that the arms 5 and 6 are provided with cut out portions 16, substantially intermediate the ends thereof and between the pivots 7, 8, 70 and the pivots 17 so that the arms 13 may be gripped by the fingers when it is desired to extend the same to the position as shown by Figure 1 of the drawing. It will also be observed that the hook 11 and particularly 80 the bent portion 12 is disposed so as to extend outwardly through the slot or recess which assumes a somewhat elliptical shape as indicated at 18, see Figure 4, in which position it will be observed that the hook 85 will lie in proper position when the hanger is collapsed.

In actual practice, it has been found that the arms 5 and 6 can be stamped of sheet metal such as aluminum, tin, or other metal 90 and that the pivots 7, 8, and 17 may be riveted so as to permit of the proper folding of the device. It will also be readily recognized that when the hanger is extended, the inner ends of the arms 5, 6, will be in contact immediately below the threaded end 10 of the hook and since the extensions 13, 14 fold outwardly, a strong, durable, and rigid construction is had to support a heavy 95 or weighted garment in the manner well 100 understood.

While I have illustrated and described my invention with some degree of particularity, I realize that in practice various alterations 105 therein may be made. I therefore reserve the right and privilege of changing the form of the details of construction or otherwise altering the arrangement of the correlated parts without departing from the spirit of the invention or the scope of the appended 110 claim.

Having thus described my invention what

I claim as new and desire to secure by United States Letters Patent is:—

A folding garment hanger comprising a pair of arms substantially U-shaped in cross section, a block positioned within the adjacent ends of the arms, said arms being pivoted to the block for swinging movement, and the inner ends of the arms adapted for abutment with each other to limit their outward swinging movement, extensions pivotally connected to the outer ends of the arms for swinging movement in alignment with and foldable within the U-shaped arms

for concealment when the hanger is collapsed, said arms being provided with recesses in their edges to facilitate gripping the extensions and a supporting wire hook for the hanger fastened to the block between the arms and having a laterally offset portion extending through the recesses when said hanger is folded whereby the bill of the hook is arranged outside of the arms and flush therewith.

In testimony whereof I affix my signature.

HENRY G. HAROLD. [L. s.]
